John Sparks INVENTOR
BY
Howard P. Hudson ATTORNEY.

UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

MOTOR.

1,355,283.

Specification of Letters Patent.

Patented Oct. 12, 1920.

Application filed March 16, 1917. Serial No. 155,262.

To all whom it may concern:

Be it known that I, WILLIAM SPARKS, a citizen of the United States, and resident of Jackson, in the county of Jackson, in the 5 State of Michigan, have invented new and useful Improvements in Motors, of which the following, taken in connection with the accompanying drawings, is a full, clear, and exact description.

10 This invention relates to certain improvements in motors.

Reference is hereby made to my co-pending application Serial No. 765,792.

15 The main object of the invention is to produce an efficient motor of simple construction and light weight, at minimum expense for materials and labor, such a motor being peculiarly adapted for use in connection with electric horn or signal.

20 The invention takes form in a device comprised entirely of pressed metal, and is an improvement upon the construction shown, described and claimed in my copending application, Ser. No. 765,792, Patent No. 25 1,237,717, dated Aug. 21, 1917.

A marked improvement resides in the form and method of producing the pole pieces and field coils, the required number of ampere turns of wire in the field coils 30 being obtained from a materially reduced quantity of wire. As an illustration, in signals of a predetermined size, each field coil has heretofore embodied approximately seventy-eight (78) feet of wire to obtain the

35 required flux, whereas in the present signal the same number of ampere turns and the same flux is obtained with approximately thirty-seven (37) feet of wire. This improvement may be effected by coiling the 40 wire to form the field coils, directly about the pole pieces, the latter being preferably of substantially circular form and of relatively small diameter.

Other objects and advantages will appear 45 from the following description, taken in connection with the accompanying drawings; in which—

Figure 1 is a side elevation of the signal.

Fig. 2 is a section on line 2—2, Fig. 1.

50 Fig. 3 is a section taken at right angles to Fig. 2.

Fig. 4 is a section taken on line 4—4, Fig. 1.

Fig. 5 is an enlarged section of the ad-

justable bearing for the rear end of the motor shaft.

The signal embodies the usual resonator 55 —1—, front case section —2—, rear case section —3—, between which case sections the periphery of diaphragm —4— is 60 clamped. The section —2— may, as shown, be provided with a circular flange —5— adapted to inclose the edge of the dia- phragm and the rear case section —3—.

Preferably the rear case section is of 65 dished formation and is provided with a transverse wall —6— substantially parallel with the diaphragm and spaced therefrom a sufficient distance to permit reasonable adjustment and efficient operation of a cam 70 —7— coating with a wear-piece —8— upon the diaphragm to vibrate the latter as the former is rotated.

The cam —7— is mounted upon the armature shaft —9— of an electric motor, the 75 shaft —9— having one bearing in the transverse wall —6— and its opposite end adjustably mounted in a transverse portion —10— of a U-shaped case —11— having its side walls —12— and —13— substantially 80 parallel with each other and lying substantially perpendicular to the transverse wall —6— and having their ends reduced and threaded and extended through said transverse wall for coaction with nuts —14— 85 and —15— for rigidly securing the U-shaped case to the rear diaphragm case section.

The U-shaped case is formed of a relatively narrow thin strip of sheet metal, as 90 sheet steel, bent in the form shown and having its transverse portion —10— provided with an internally threaded opening for coaction with an externally threaded bearing —16— adjustable through said transverse 95 portion and having a recess —17— provided with an overhanging flange —18—.

The adjacent end of shaft —9— may be locked in this recess in any suitable manner so as to be positively moved toward and 100 from the diaphragm upon movement of said bearing through the transverse portion, and, for this purpose and as illustrative of one suitable construction, the shaft —9— is provided with a recess which may extend 105 circumferentially of the shaft for the reception of a spring ring —19— adapted to be seated in the recess when the same is

passed through the restricted portion formed by flange —18— and to expand under its own resiliency after passing the flange —18—, to engage the inner surface 5 of said flange and prevent removal of the shaft from the bearing and cause the shaft to move positively with the bearing. The bearing may be locked relatively to the transverse wall —10—, if desired, by a suitable lock nut —20—.

The side portions —12— and —13— carry suitable brushes —21— for contact with the commutator —22— upon the armature shaft. These brushes may be supported 15 in any suitable manner, and as shown are slidably mounted in housings —23— secured to the respective walls —12— and —13— by screws —24—, each brush being pressed into contact with the commutator 20 by spring —25— and provided with a spring finger —26—, as shown, having one end extending within the housing —23— and its opposite end in contact with the brush outside the housing for transferring current 25 directly from the brush to the housing without the necessity of the current passing through the spring, the finger preferably being formed of material of greater conductivity than the spring. This is advantageous 30 by reason of the fact that the heat generated by the passage of electricity through the spring tends to decrease, and ultimately destroy, its resiliency.

The side portions —12— and —13— carry 35 inwardly projecting studs —27— secured to the side portions in any suitable way, as by welding, flanging, or the like. In this illustration the side walls are provided with openings through which the studs extend, 40 the ends of the studs being flanged, riveted or welded into engagement with the side portions, and preferably the welded or flanged parts are countersunk within said portions.

45 The studs are preferably provided with enlarged portions —28— adapted to abut against the interior of the side portions —12— and —13—, and these enlarged portions are in turn provided with projections 50 —29— extending through the plate-like portions or pole shoes —30— of the pole pieces and flanged, welded or riveted into engagement with said plate-like portions to hold the same in rigid condition.

55 The studs —27— and plate-like portions —30— constitute the pole pieces.

Instead of having field coils as independent articles of manufacture for mounting upon the pole pieces, the wire for forming 60 the coils is wound about the enlarged portions —28— of studs —27— to constitute sufficient ampere turns, such coils 31 being circular in form and of relatively small diameter and confined between the plate-like parts —30— and the side portions

—12— and —13—, respectively. The wire from which the field coils are formed may be covered with any suitable insulating composition or material.

The plate-like portions of the pole pieces 70 are preferably, as shown, of a conformation adapted to conform to and surround the adjacent portion of the armature —31— and may, as shown, be angular in form having a central portion and opposite side portions 75 extending therefrom and lying in three separate planes substantially tangent to their respective adjacent portions of the commutator.

Preferably the transverse wall —6— is 80 provided with openings permitting the passage of the wires or other conductors from the field coils to terminals —32—, the opposite ends of the wires being electrically connected in the usual manner to the brushes 85 —21—.

Preferably the U-shaped case and the remaining portions of the motor are inclosed by a cup-shaped casing —33— having its open end fitted over the rear diaphragm 90 case section —3—. The casing may be secured to the U-shaped case in any suitable way, as by screw —34—, if desired.

Suitable insulating material in sheet or plate form is utilized where desired, as in 95 spacing the field coils from the pole pieces, etc., and although I have shown and described a specific construction, form and arrangement of parts as perhaps preferable, I do not desire to limit myself to the same 100 as many changes may be made in the details of each without departing from the scope of this invention as set forth in the appended claims.

What I claim is:—

1. A motor comprising a U-shape sheet metal frame having oppositely disposed openings in the side walls thereof, pole pieces each comprising a central portion and a pair of studs extending from opposite 110 ends thereof, respective studs extended through the openings in the said frame and permanently secured to the frame, sheet metal pole shoes having openings through which the other respective studs extend, 115 the studs and pole shoes being permanently secured together and said pole shoes extending laterally from the pole piece, wire wound tightly about the pole pieces and confined between the pole shoes and the U-shape 120 frame and an armature positioned between the pole shoes.

2. A motor comprising a U-shape sheet metal frame having reduced end parts, an end wall extending across the open end of 125 the U-shape frame and having a pair of openings through which the reduced end portions of said U-shape frame extend and means mounted on the reduced end portions for rigidly securing the U-shape frame to 130

said end wall, said U-shape frame having oppositely disposed openings in the side walls thereof, pole pieces each comprising a central portion and a pair of studs extending from opposite ends thereof, respective studs extending through the openings in said frame and permanently secured to the frame, sheet metal pole shoes having openings through which the other respective 5 studs extend, said studs and pole shoes being permanently secured together and said pole shoes extending laterally from their

respective pole pieces, wire tightly coiled about the pole pieces and confined between the pole shoes and the U-shape frame and 15 an armature having its shaft mounted in the base of the U-shape frame and the end wall and rotatable between said pole shoes.

In witness whereof I have hereunto set my hand this 28th day of February, 1917. 20

WILLIAM SPARKS.

Witnesses:

WILLIAM WUNDERLICH,
N. J. CARLETT.
